BEVEL CUTTING TIP

Floyd I. Hartung, Portsmouth, Va., assignor to
 The Bastian-Blessing Company, Chicago, Ill.,
 a corporation of Illinois

Application January 8, 1945, Serial No. 571,902

5 Claims. (Cl. 158—27.4)

The present invention relates to blowpipes and more particularly to blowpipes and processes in which a mixture of oxygen and a liquefied petroleum gas such as propane or butane is employed for the preheat flames in cutting and washing ferrous metals.

Although the present invention is of particular interest for bevel cutting and washing steel plates, as where the cutting stream of oxygen is directed at an acute angle to the face of the plate, it also constitutes a marked improvement in cutting practices over those conventionally used where the metal is to be lanced or cut at right angles to the face of the plate. Consequently, wherever in the description and claims the word burning is used in describing the process of the invention and the operation of the tip, cutting, washing and lancing will be contemplated.

Burning a ferrous metal involves the rapid chemical reaction between heated iron and oxygen in which iron heated to its ignition temperature and exposed to high purity oxygen will oxidize with an intense reaction to liberate heat and form oxides which are discharged as slag. As a general rule, the heating of the metal to its ignition point is accomplished by a so-called preheat flame which serves as a pilot for the ignition of metal on its surface when a stream of oxygen is turned on to impinge the heated area of the metal. Thereafter the intense heat liberated helps to pilot the ignition of the deeper portions of the metal to the extent that oxygen is available and according to the character of the oxygen stream. The oxides formed are molten and flow or are blown away exposing more metal to the action of the oxygen. If the burning action is started at the edge of the metal piece the successive oxidation and removal of oxides will take the form of a groove down the side of the piece.

The heat resulting from the reaction, however, is not enough to keep the reaction going because of the chilling effect of the surrounding metal and the stream of cutting oxygen in conventional practices. Therefore, it is necessary in most cases to supply further heat to the point of burning to heat progressively to the ignition point the leading edge of the cut as the stream of cutting oxygen is advanced along a predetermined path. Thereby the initial groove is deepened into a kerf.

By changing the pressure of the oxygen stream, its flow characteristics, the direction of impingement with respect to the metal surface and the speed with which the stream of cutting oxygen is advanced, the burning action generally can be made to produce different types of cuts.

Conventional tips using propane and oxygen as a preheat fuel have the preheat ports arranged in a predetermined pattern around the port through which the stream of cutting oxygen

is discharged. The preheat streams are directed to flow along lines approximately parallel with the cutting stream within a shielding wall extending appreciably beyond the ports. Various shapes of preheat ports are provided, some being deeper in a radial direction than they are wide peripherally while others have various geometrical cross-sectional contours. In all of these tips the inner edge of all preheat ports are spaced from the cutting port by metal stock required for structural reasons and the flames are directed to one side of the point of impingement of the cutting stream upon the work. This increases the working area of the preheat flames and since the metal has to approach white heat for ignition, much heat is wasted before the point of impingement by the cutting stream becomes ignition hot.

In the present invention the preheat flames are directed inwardly in a concentrated cone to convey their heat directly to the point of impingement by the cutting stream. In doing this, all of the flames supply heat to a limited area and provide a faster starting preheat and a faster working preheat as compared with conventional tips where some of the flames miss the edge of the metal at the start and engage the metal only along a path paralleling the projected kerf.

A further difficulty is experienced with conventional tips in that the preheat flames spread laterally and away from the point of cutting impingement when they strike the metal. This condition is particularly augmented in bevel cutting. In the present invention this difficulty is overcome by directing the flames to mutually converge at an acute angle with respect to each other in a manner counteracting their tendency to spread until after their effective heat has been delivered to the metal where the burning is to take place.

A further difficulty is encountered with conventional tips in that the slag or oxides are caught in an envelope of flaming gases which hinders escape of the oxides except through the kerf, whereas, in the present invention one of the objects is to direct the flaming gases to a point of convergence to prevent oxide and slag from bouncing and clinging to the tip and to blast the slag laterally from the point of convergence. In this way the tip is kept cleaner, runs cooler, and is provided with a longer life.

Another object of the invention resides in preheating an area limited to only that necessary to make the cut, thereby saving fuel and cutting oxygen and providing a narrow and clean kerf.

The invention is further characterized by a convergence pattern of the preheat flames in which the cutting tip can be brought closer to the work than possible conventionally whereby the stream of cutting oxygen can impinge and oxidize the metal to start the kerf before the stream has a chance to expand after leaving the cutting port.

Another object of the invention is to provide a propane-oxygen cutting tip which permits a faster cutting speed so that the speed is limited to the speed available with the cutting stream rather than with the preheat.

A further object of the invention is to provide a tip which runs so cool that slag will not adhere to it and which so concentrates the flames that the cutting stream must pass through a wall of flame on its way to oxidize the metal. Furthermore, the flame is carried by the cutting oxygen into the cut to maintain a proper piloting action along the leading side of the kerf as well as the edge thereof.

Another object of the invention is to provide an improved process for heating the cutting oxygen and for cutting non-magnetic steel by pre-heating the stream of oxygen before it contacts the surface of the metal.

These being among the objects of the invention other and further objects will appear from the drawing, the description relating thereto and the appended claims.

In the drawing:

Fig. 1 is a side elevation of a machine carried blowpipe illustrating the use of the invention for bevel cutting.

Fig. 2 is a section taken longitudinally through the tip embodying the preferred form of the invention.

Fig. 3 is a section taken upon the line 3—3 in Fig. 2.

Fig. 4 is a section taken upon the line 4—4 in Fig. 2.

Fig. 5 is an enlarged section of the end of the tip shown in Fig. 2, and

Fig. 6 is an enlarged section showing another embodiment of the invention.

Referring now to the drawing in further detail a work piece 10 is shown upon a table or platform 11 with a removable track 12 resting thereon. A carriage 13 is mounted upon the track to move along on the track at a predetermined speed as supported by wheels 14. The carriage supports an arm 15 adjustable as to height by a hand wheel 16 and the arm carries a torch body 17 adjustable both as to position and angle.

Oxygen for the preheat flames and for cutting is supplied to the torch body from a high pressure cylinder 18 through a cylinder valve 20, a two-stage pressure reducing regulator 21, a hose 22 and a needle valve 23 for the fuel mixture and a cutoff valve 24 for the cutting stream. Propane for the preheat flames is supplied to the torch body from a cylinder 25 through a cylinder valve 26, a two-stage pressure regulator 27, hose 28 and the needle valve 30.

At its free end, the torch body is provided with a head 31 threaded to receive the tip nut 32 which holds the tip 33 rigidly in place in a conical cavity (not shown) upon the head 31 as more particularly described in the Wigton Patent 2,335,330, reference to which is hereby made. The cavity is provided with suitable grooves separated by sealing lands (not shown) by which gases are conveyed to the tip 33 without mixing, the cutting oxygen entering at the apex of the cavity.

The tip 33 comprises a base 34 which mates with the cavity in the head as provided with corresponding grooves 35 and 36 separated from each other and sealed off by lands 37 defining a conical surface of revolution.

A longitudinal passage 40 is formed in the base, enlarged as at 41 adjacent to its downstream end

5 to provide a shoulder 42. The enlarged portion 41 is internally threaded to receive a tip core 43 with the inner end of the core sealing against the shoulder 42 and with intermediate mating cylindrical surfaces provided for mutual alignment as indicated at 44.

10 Although the tip shown is a so-called tip mixing tip; i. e. the fuel and oxygen are mixed in the tip, other tip forms may be used with the invention as where the preheat fuel and oxygen are mixed before reaching the tip. To accomplish mixing in the tip there are several passages 45 provided through the base from the groove to conduct preheat oxygen to the tip core as mixed 15 with propane which is supplied through oblique passages 46 leading from the groove 36. Thus confluence of the propane and oxygen is had in the passages 45 as controlled by the needle valves 23 and 40. From the head the confluent gases 20 are conducted to the downstream face 47 of the head 34.

The tip core 43 is formed generally of a body portion provided with a central passage 48 in communication with the passage 40 for the oxygen cutting stream. The outside of the core is tapered or inclined as at 50 and a plurality of preferably symmetrically arranged slots or grooves 51 are cut longitudinally in the exterior of the core. As seen in Fig. 4 these slots are preferably arranged around the passage 48 with their radial depth preferably greater than their width where they are formed with square bottoms, or their depth about the same as their outer width if formed with a triangular sectional contour.

30 35 Associated with the core and base is a sleeve 52 radially flanged at its base as at 53 to provide an end wall 54 which rests in sealed relationship against a land 55 provided upon the face 47 of the core. The forward side of the flange 53 provides a shoulder 56 against which the nut 32 engages to hold the core, base and sleeve in assembled relation and snugly in place upon the head 31.

45 50 The sleeve is spaced from the core over a portion of its length beginning at the base 34 to provide an annular passage 57 for the flow of the fuel-oxygen preheat mixture to the slots 51. The face 54 is rounded as at 58 into the passage 57 to provide a free flowing contour for the fuel-oxygen mixture from the chamber 60 provided by the walls 47 and 54 and sealed by the land 55 where the fuel oxygen is subjected to a further mixing action.

55 60 The sleeve 52 is tapered as at 61 to follow the contour of the taper 50 on the core at its front end whereby gases flowing through the annular passage 57 are confined to the slots 51 as they leave the passage 57 to be conducted to the end of the core.

65 70 At its outer end, the sleeve 52 extends as at 63 beyond the front end 64 of the core 43 to provide a flame piloting and shielding wall at 65. At its extreme outer end the sleeve is upset inwardly to provide a radial flange 66 which obstructs or lies within a projection of the ports of the passages 51 with respect to the direct discharge of gases from the passages 51 and redirects their flow convergently inwardly where their maximum effective heat of combustion is concentrated in the path of the cutting oxygen a little in front of the flange 66 where the confluent flames preheat the metal to its ignition point over an area slightly larger than the impingement area of the stream of cutting oxygen.

The control of this convergence and confluence of flames is established effectively when the flange 66 extends inwardly far enough to obstruct substantially a major portion of the port area of the slots 51, maximum convergence very close to the end of the sleeve being obtained when the ports are almost completely covered.

Whether the flange be rectangular in its sectional characteristics as shown in Fig. 5 or triangular as shown at 66a in Fig. 6 is of slight consequence from the functional viewpoint, the rectangular construction shown in Fig. 5 being preferred because slight burning away of the end of the sleeve which occurs under certain conditions does not change the confluence characteristics of the flames whereas a burning away of the end shown in Fig. 6 would to some extent.

In operation, it is desirable to have the flange 66 cover the outer 75 per cent of the port area. This enables the handling of the torch as operators are accustomed to using a torch with the freedom that they can get closer to the work if they desire, a thing they will do automatically as a natural thing when they become familiar with the tip constructed as described.

When the tip is brought to within $\frac{3}{8}$ to a $\frac{1}{4}$ of an inch of the work, the flames will be concentrated over the impingement area of the cutting stream of oxygen. Once the metal is brought to its melting point the cutting stream is turned on and the cut begins. The oxygen stream passes through the flame confluence and impinges upon the work. Thereafter the carriage 13 is started and as the tip is moved along the projected kerf, the oxygen passing through the concentration of flame spreads the flame effect slightly around it to heat the metal along and in the projected kerf. Thus, once the cut is started, the flame is spread automatically to take in a wider area sufficiently to provide a fast cutting preheat.

Furthermore, with the cutting oxygen passing through the flame wall, the outer edges are heated and the flame is carried down into the kerf to eliminate much of the cooling effect which is a burden upon cutting operations, particularly fast cutting.

Whenever the tip is set at an angle to the work for bevel cutting, the flame confluence still engages the point of cutting impingement and the angle of the bevel is limited only by the edge of the tip dragging on the work.

When cutting non-magnetic steel, it has been found that the preheating of the stream of cutting oxygen is an advantage to provide clean cuts. This heating is augmented by lifting the tip as much as one inch away from the work in some instances to provide a longer period of contact between the confluent flames and the oxygen. This eliminates undue breakdown of the kerf edges and with thin pieces provides a uniform cut free from burns and slag.

Throughout the operation of the tip described, any puddling or movement of slag or oxides is subjected to a focal draft induced by the converging flames and burnt gases. This focus is generally between the end of the tip and the work. Therefore, the slag is blown laterally away from the tip and prevented from bouncing or entering the end of the sleeve. For this reason the tip works cleaner and has a longer life.

Consequently, having thus described the invention, its modifications and functional relationships, it will be readily apparent to those skilled in the art how the objects mentioned are accom-

plished and how various and further modifications and changes can be made without departing from the spirit of the invention, the scope of which is commensurate with the appended claims.

5. What is claimed is:

1. In a blowpipe tip, means defining a plurality of gas passages through which streams of a combustible fuel and oxygen mixture are conducted and terminating in ports through which the streams are discharged in approximately parallel relationship and means including a wall extending beyond the ports parallel with the respective combustible fuel passages and terminating in a flange lying partly within a projection of the ports with respect to the path of said streams.

2. In a blowpipe tip, means defining a plurality of gas passages through which streams of a combustible fuel and oxygen mixture are conducted and terminating in ports through which the streams are discharged in approximately parallel relationship, and means including a wall extending beyond the ports parallel with the respective combustible fuel passages and terminating in a flange defining a frusto-conical wall lying partly within a projection of the ports with respect to the path of said streams.

3. In a blowpipe tip, means defining a plurality of gas passages through which streams of a mixture of liquefied petroleum gas fuel and oxygen are conducted and terminating in ports through which the streams are discharged in approximately parallel relationship, and means including a wall extending beyond the ports parallel with the respective combustible fuel passages and terminating in a means for directing the radially outer portions of the streams convergingly inwardly at an acute angle after the streams leave the ports including a flange lying partly within a projection of the ports with respect to the path of said streams and defining an approximately cylindrical opening through which the streams pass.

4. In a tip construction for blowpipes the combination of a central portion having a passage therein for discharging a stream of cutting oxygen along a predetermined path, a sleeve co-operating with the core to form conduits to discharge streams of preheat mixture around the passage, said sleeve defining a wall extending beyond the ports parallel with the respective combustible fuel passages, said sleeve including means beyond the wall disposed within a projection of the ports with respect to the path of the streams to direct the streams of preheat mixture sharply inwardly to converge in the path of said stream of cutting oxygen at the point where the oxygen stream is expected to impinge upon a work piece to be cut.

5. In a tip construction for blowpipes, the combination of a central portion having a passage therein for discharging a stream of cutting oxygen along a predetermined path, a sleeve co-operating with the core to form conduits to discharge streams of preheat mixture through ports arranged around the passage, and an inwardly extending flange upon the sleeve spaced from said ports to provide an ignition area and lying partly within a projection of the ports with respect to the path of said streams to direct the outer portions of the streams sharply inwardly to converge in the path of said stream of cutting oxygen.

FLOYD I. HARTUNG.
